UNITED STATES PATENT OFFICE.

MARTIN G. GAMBSKY, OF MENASHA, WISCONSIN.

MOLD FOR FORMING THE LOWER SECTIONS OF MANSARD ROOFS UPON BUILDINGS.

1,119,818.

Specification of Letters Patent.

Patented Dec. 8, 1914.

Application filed February 24, 1914. Serial No. 820,527.

To all whom it may concern:

Be it known that I, MARTIN GEORGE GAMBSKY, a citizen of the United States, residing at Menasha, in the county of Winnebago and State of Wisconsin, have invented a new and useful Improvement in Molds for Forming the Lower Sections of Mansard Roofs Upon Buildings, of which the following is a specification.

My invention relates to a Mansard roof for buildings, and is particularly adapted for silos, but it evidently can be used upon other buildings in which the walls are formed of cement, concrete, brick, &c., but will be shown as applied to a silo and described as so applied, and is designed for molding the steeper part of a Mansard roof, the advantages of which over the usual roof being that several feet in height are added to the capacity of the building and a better architectural design presented, while the increased cost is but little. The molds are made in sections and bolted together for use, the band molds for the wall of the building, the cornice supporting shelf and the in and outside rings which are used with the molds being formed in the illustration in six sections each, and the mold plates for the inclined roof in a greater number of sections, but no particular number are essential, they depending upon the size of the building.

The invention consists of two bands, one for the inside and one for the outside, both to be secured in position upon the upper edges of the band molds between which the side wall has been formed, a plurality of shelf supporting brackets, a cornice supporting shelf mounted upon said brackets, a series of tapering mold plates mounted upon both the outer edge of the cornice shelf and the upper edge of the inner band mold, all of which are best formed of sheet metal, angle and other shaped irons, a ring being arranged at the upper ends of the roof mold plates, both inside and outside thereof, the latter serving as a cornice mold for the less inclined part of the roof, all of which parts are shown in the accompanying drawing, in which—

Figure 1 is a plan, which at the left hand section of the band mold shows the upper mold bands between which the main wall of the silo has been built up and is filled with cement, the two sections at the right showing bands mounted upon the first named bands but not yet filled with cement, the

outer ones being each provided with a plurality of brackets and the inner ones with a plurality of bars vertically arranged, and the right hand half shows the cornice supporting shelf in position upon the brackets. Fig. 2 is a side elevation of the outside of one of the outer band sections. Fig. 3 is a side elevation of the inside of one of the inside band sections. Fig. 4 is a complete vertical section of a Mansard roof. Fig. 5 is an elevation of the outside of one of the outer tapering sections which forms the outer mold plate for the roof. Fig. 6 is a section of said mold plate upon the line *a*, *a*, of Fig. 5. Fig. 7 is an elevation of the inside of one of the inner tapering sections which forms the inner mold plate for the roof. Fig. 8 is a section of said mold plate upon the line *b*, *b*, of Fig. 7. Fig. 9 is an elevation partly in section, of the inner and outer tapering mold plates upon the line *c*, *c*, of Fig. 18, mounted upon their respective band molds. Fig. 10 is an elevation of a bracket for supporting the cornice shelf. Fig. 11 is a modification in the form of the bracket. Fig. 12 is an elevation of an inside tapering mold plate section, mounted in position upon the inner band mold, said band mold being mounted upon the upper mold piece of the silo wall. Fig. 13 is a plan of one end of cornice shelf segments and showing the manner of holding the ends in position. Fig. 14 is a transverse section of the left hand end of Fig. 13. Fig. 15 is a transverse section of the right hand end of Fig. 13. Fig. 16 is an elevation of the outer ring at the top of the tapering mold plates and showing the manner of connecting the several sections thereof. Fig. 17 is a plan of the inside tapering mold plates in position around a silo with the cornice shelf in position for receiving the outer tapering mold plates. Fig. 18 is a plan of the outer tapering mold plates in position around a silo. Figs. 1, 4, 17 and 18, are upon a smaller scale than the others.

Similar numerals and letters indicate like parts in the several views.

1, indicates the wall of a building formed of cement for use as a silo; 2 and 3, the outer and inner molds between which the wall was formed in a well known manner; 4 and 5, are outer and inner mold bands of my invention, formed in sections as has been described, the outer band sections 4, having each a plurality of loops 6, for receiving

brackets 7 or 7^a, and which extend above the bands 4 and 5 for supporting a cornice shelf 8, and each inside band section 5, is provided with a plurality of bars which form 5 fingers 9, that extend above the upper edge of said band for assisting in holding the tapering mold plates in position upon the band mold 5. The loops 6 may be secured to the band 4, with rivets or otherwise, and the 10 brackets be formed of bar iron of a suitable size and form. The cornice shelf 8, is formed of sheet metal, cut to the required curve, and has around its outer edge an angle iron 10, with the longer leg of the angle arranged 15 vertically and outwardly for holding the lower ends of the tapering mold plates, which inclose the outside of the roof, in position.

The tapering mold plates may all, both 20 for the outer and inner side of the wall be of substantially the same taper, length and width, but more of them will be required for the outer than for the inner side of the wall. Both the outer and inner plates 11 and 12, are provided along their tapering edges with flanges, which flanges may be of angle iron 13, and be provided with a plurality of holes 14, for receiving connecting bolts 15, as in Fig. 12, the bolts through the 25 flanges of the outside tapering mold plates in Fig. 18 showing but one for want of space thereon. Around the top of the inner tapering mold plates a ring 16, is mounted upon the flanges 13, for preserving a circular form to the roof, as is shown in Figs. 9 and 17, and arranged upon the outer mold plates is a ring 17, formed of angle iron with one of the legs of the angle outwardly and vertically arranged and serving as a shelf 30 upon which to form a cornice for the upper and less inclined part of the roof. The inner tapering mold plates are each provided with an angle iron rib 18, which is secured to it longitudinally thereof and has at 35 its lower end a finger 18^a, which extends downward on to the band mold 5, and in connection with the fingers 9 upon said band retain the tapering mold plate upon the band 5. For spacing the upper ends of the 40 outer tapering mold plates from the inner ones, the outer ends of the brackets are provided with a perforation 20, (see the ends 18 and 19, Figs. 10 and 11), for receiving a wire or small rod, as 21, in Fig. 11. The 45 upper end of the rod is formed into a hook and is hooked over the upper edge of the tapering mold plate and by swinging it to the right and left along said upper edge, the 50 distance between the bracket end and tapering mold plate top can be changed, within certain limits, as is shown in dotted lines, upon one in Fig. 18, that is applied to a bracket 7^a. A preferable method is shown 55 in the use of the brackets 7 of Fig. 10. In this case a rod 21^a, is threaded and provided

with a nut 22, the threaded end passed through the perforation 20, and its upper hooked end hooked over the upper edge of a tapering mold plate.

By screwing the nut on and off the mold 70 plate can be swung inward or outward as the case demands with reference to the inner mold plates. The two rings are made in sections for convenience in transportation and storage and the several sections can be 75 connected by bolting a piece as 23, in Fig. 16, to adjoining ends. The cornice shelf sections are each provided with a tongue 24, and socket 25, which may be of sheet metal and be soldered to the main sheet, the tongue 80 being fitted to enter the socket and hold the two ends in position.

In Fig. 18, the position of the ring 16, is shown in dotted lines, the inner tapering mold plates not being shown in said figure. 85

In Figs. 1, 4, 9 and 17, the cement filling is indicated by 26. In Fig. 4, the additional cement filling which is made with the use of my band molds is indicated by *a*, the cornice of the lower section of the Mansard roof by *b*, the less inclined part of the roof by *c*, and the cornice for the upper and more inclined part by *d*. After the molds have been filled and the roof completed up to the cornice *d*, the balance of the roof can be 95 formed with molds already in use, in a well known manner.

Having described my invention, what I claim and desire to secure by Letters Patent, is,—

1. In a mold for the lower section of a Mansard roof for a building, an outer and inner band mold around the upper end of the building wall adapted to be supported upon the molds between which the wall was 105 formed, a plurality of brackets upon the outer band molds, a perforation through the outer end of each bracket, a cornice forming shelf mounted around said outer band mold upon said brackets having an upstanding rim around its outer circumference, a plurality of tapering mold plates, each having means for securing one to the other, arranged around the outer edge of the cornice forming shelf and within the upstanding rim aforesaid, a rod connecting the upper edge of a tapering mold plate with a bracket, and a plurality of like tapering mold plates as said outer ones aforesaid, mounted upon the upper edge of the inner band mold and a ring around their upper ends inside thereof.

2. In a mold for the lower section of a Mansard roof for a building, an outer and inner band mold around the upper end of the building wall adapted to be supported upon the molds between which the wall was 125 formed, a plurality of brackets upon the outer band mold, a perforation through the outer end of each bracket, a cornice forming

shelf mounted around said outer band mold upon said brackets having an upstanding rim around its outer circumference, a plurality of tapering mold plates, each having 5 means for securing one to another, arranged around the outer edge of the cornice forming shelf and within the upstanding rim aforesaid, a rod threaded at one end and provided with a nut and having a hook at 10 the other end adapted to be hooked over the upper end of a tapering mold plate and be connected with a bracket through a perforation therein, and a plurality of like tapering mold plates as said outer ones aforesaid mounted upon the upper edge of the inner 15 band mold and a ring at their upper ends inside thereof.

MARTIN G. GAMBSKY.
